United States Patent Office

Des. 215,303
Patented Sept. 23, 1969

215,303

STAND FOR A SELF-CHARGING HAIR CLIPPER

Herbert R. Carpenter, Chicago, Ill., assignor to Andis
Clipper Co., Racine, Wis., a corporation of Wisconsin
Filed Dec. 5, 1968, Ser. No. 14,815

Term of patent 14 years

Int. Cl. D13—02

U.S. Cl. D26—15

FIG. 3

FIG. 4

FIG. 5

FIG. 6

FIG. 1 is a front view in perspective of a stand for a self-charging hair clipper embodying my new design.

FIG. 2 is a rear view in perspective of a stand for a self-charging hair clipper.

FIG. 3 is a view thereof in top plan.

FIG. 4 is a view thereof in side elevation.

FIG. 5 is a view thereof in front elevation.

FIG. 6 is a view thereof in rear elevation. The bottom is plain.

I claim:

The ornamental design for a stand for a self-charging hair clipper, as shown and described.
